CLAIM

The ornamental design for a metal detecting machine, as shown and described.

DESCRIPTION

FIG. 1 is a perspective view of a metal detecting machine showing my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken lines depict portions of the metal detecting machine in which the design is embodied that form no part of the claimed design.
